UNITED STATES PATENT OFFICE.

JOHN A. HAY, OF NEW PHILADELPHIA, OHIO.

COTTER-PIN TOOL.

Application filed December 27, 1922. Serial No. 609,248.

To all whom it may concern:

Be it known that I, JOHN A. HAY, a citizen of the United States, residing at New Philadelphia, in the county of Tuscarawas and State of Ohio, have invented new and useful Improvements in Cotter-Pin Tools, of which the following is a specification.

This invention relates to tools and has for its object the provision of a novel tool 10 for the purpose of spreading and properly bending the cotter pins for holding them in position.

An important and more specific object is the provision of a tool of this character 15 which is formed in one piece and which is operated by one hand, the device including a chisel-like wedge member initially insertable between the prongs of a cotter pin for effecting spreading, and the tool further including side lugs or wings by means 20 of which the prongs of the cotter pins may subsequently be bent to the desired angle.

An additional object is the provision of a tool of this character which will be simple and inexpensive in manufacture, highly efficient in use, durable in service and a general improvement in the art.

With the above and other objects and advantages in view the invention consists in 30 the details of construction to be herein-after more fully described and claimed and illustrated in the accompanying drawings, in which:

Figure 1 is a perspective view of the 35 tool.

Figure 2 is an elevation thereof showing the first use thereof to spread a cotter pin and

Figure 3 is a similar view showing the 40 tool used for subsequently bending the prongs of the cotter pin.

Referring more particularly to the drawings I have shown the tool as comprising an elongated shank 10 formed of suitably 45 tempered steel. While it is not necessary I have shown and prefer to provide one end of this shank with a hammer head 11 having the usual claw 12 so that the tool will be adaptable for use for more than 50 one purpose. The other end of the shank is cut away at both sides as shown at 13 to define an elongated wedge 14 and formed

integrally upon one edge of the wedge shaped portion near the end thereof are laterally extending curved lugs or hooks 15 55 which are of course spaced away from the sides of the wedge shaped end.

In the use of the device, the cotter pin A is placed through the hole B in the piece C to be secured and the operator then inserts the end of the wedge 14 between the prongs of the cotter pin and pries the prongs apart. After this is done, the operator removes the tool from the initial position described and then engages the wedge 65 14 and one lug 15 against the outside and inside of a prong respectively and pries again to bend the prong to the proper angle to insure proper holding action of the pin. Both prongs of the cotter pin are of course 70 treated in the same manner and it will be apparent that after the bending is effected there will be no question as to the holding power. The hammer end of the tool is used for further bending or straightening up 75 cotter pins to be removed and in this way it is apparent that the tool will be a great time and labor saver and consequently a boon to automobile repair men and other mechanics.

While I have shown and described the preferred embodiment of the invention it is of course to be understood that I reserve the right to make such changes in the form, construction and arrangement of parts as 85 will not depart from the spirit of the invention or the scope of the subjoined claims.

I claim:

1. A tool of the character described comprising an elongated shank having one end 90 tapered into a wedge shape and provided at opposite sides of the wedge with lugs overlying the same and spaced therefrom.

2. A tool of the character described comprising an elongated shank having one end 95 tapered into a wedge shape and provided at opposite sides of the wedge with lugs overlying the same and spaced therefrom, the lugs being formed integrally with the shank and extending substantially entirely 100 across the wedge.

In testimony whereof I affix my signature.

JOHN A. HAY.
